UNITED STATES PATENT OFFICE.

JOHN J. SIBLEY, OF NEW YORK, N. Y.

IMPROVEMENT IN SEWING-MACHINES.

Specification forming part of Letters Patent No. 42,117, dated March 29, 1864.

To all whom it may concern:

Be it known that I, JOHN J. SIBLEY, of the city and county of New York, State of New York, have invented certain new and useful Improvements in Sewing-Machines; and I do hereby declare that the following is a full and correct description thereof, reference being had to the annexed drawings, and to the letters of reference thereon.

My said invention relates to the sewing-machine well known as the "Wheeler & Wilson sewing-machine;" and its object is to enable said machine to sew the double-looped stitch, and also to change at pleasure from the lock-stitch to the double-looped stitch, or vice versa.

A part of my invention consists in combining with the needle-rotating hook and other operative parts of a Wheeler & Wilson sewing-machine (except the bobbin and ring-slide) a vibrating under-thread carrier operated by the machine to make the double-looped stitch, as follows: When the loop of needle-thread has been caught and spread by the rotating hook and the needle retracted, leaving its loop of needle-thread spread upon the hook, as in the ordinary operation of the Wheeler & Wilson sewing-machine, the under-thread carrier, with its thread, passes through said loop of needle-thread, carrying its own thread back of the track of the needle, in which position it remains until the needle has again descended and retracted, thus introducing a loop of under-thread through the loop of needle-thread, and holding the loop of under-thread in position for the downward stroke of the needle to pass a loop of needle-thread through it, which is done by the needle descending in front of the thread-carrier and its thread. As soon as the needle has again retracted, leaving its loop of needle-thread caught upon the rotating hook and interlooped with the under-thread, the thread-carrier moves out in front of the rotating hook and loop of needle-thread. The loop of needle-thread being meantime spread open by the rotating hook, the under-thread carrier immediately moves in through said loop of needle-thread, carrying its under-thread through the loop of needle-thread to a position back of the track of the needle, and holding it there to be interlooped with the needle-thread by the downstroke of the needle, as before, the result of the repetition of the movements

of the rotating hook, needle, and vibrating under-thread carrier being to form stitches from two threads by interlooping them alternately with each other, the rotating hook performing the operation of seizing and spreading the loops of needle-thread, also of drawing or tightening the stitches and carrying the loops of needle-thread out of the way of the needle and casting them off, as in the Wheeler & Wilson sewing-machine. The ordinary pad or loop check used in the Wheeler & Wilson machine co-operates with the revolving hook to detain the loops, as in the ordinary operation of the said Wheeler & Wilson sewing-machine; but, the bobbin and ring-slide being removed, a further provision is necessary to prevent the loop just being cast off from the revolving hook from falling over and being again caught by the hook. If the construction herein described were so modified as to retain the bobbin (unthreaded) and a supporting-ring, such provision would not be necessary; but when the bobbin and ring are dispensed with it becomes necessary to detain the loop after it has escaped from the old or first pad or loop check by a second pad at a higher point on the revolving looper, where the loop, which is at this time rapidly shortening, may be detained without breakage; and this part of my invention further consists in the application and use of a second loop-pad, applied to the hook at a point higher up than the usual pad on the machine, for the purpose of preventing the loop just being thrown off from the hook from interfering with the formation of the stitcher.

My invention further consists in organizing the under-thread carrier, together with the lever, by which motion is communicated to it in a frame separate from and independent of the sewing-machine frame, but adapted thereto in such manner, as is hereinafter more particularly described, that to change from the ordinary lock-stitch to the double-loop stitch the operator has only to remove and lay aside for the time the bobbin and ring-slide, to place the frame containing the separately-organized thread-carrier in the place of the bobbin-ring slide, and screw it fast to the seat by a thumb-screw, the parts being so arranged that when this is done the lever which operates the thread-carrier is brought into operative prox-

inity with the cam, which advances the cloth, which then also gives motion to the thread-carrier in one direction, a spring reacting it. The second pad may be placed upon the frame of the separate organization; also the spool-holder for the under thread, as herein shown; but this is not of necessity, although a great convenience to have the separately-organized attachable part of the machine contain all the additional parts required to make the double-looped stitch. Now, it is well known that the Wheeler & Wilson sewing-machine is in widely-extended use in the United States and adjacent countries, making the lock-stitch only; and it is also well known that the different sizes of said machines are numbered, and that the respective parts of all the machines of a given size are made to conform to gages, so that the same parts of each machine of any given size are alike. Therefore there is no difficulty in making my separate organization of thread-carrier of different sizes, so as to be adapted to and correspond with every Wheeler & Wilson machine of the same numbered size; and thus my invention possesses great utility beyond adding a stitch to the Wheeler & Wilson sewing-machine, because of its being applied to use in such manner that any one having a Wheeler & Wilson machine can, by sending the size, procure from a distance the separately-organized thread-carrier, and set it at work upon the machine as readily as a hemmer or other attachment to said machine.

But more particularly to describe my said invention, I will refer to the drawings by letters of reference.

Sheet 1 contains Figure 1, a side elevation of a Wheeler & Wilson sewing-machine having the bobbin and ring-slide removed and my improvements attached; and Fig. 2, a top view of the same with the table removed in order to show the operative parts. Sheet 2 contains detached views of different parts, the same letters of reference indicating the same parts in all the drawings.

The frame *a* of the separate organization is secured to the seat of the removed ring-slide by the thumb-screw *b*, a gage-pin, *c*, projecting from the frame *a*, determining its position. The under-thread carrier *d* is fast to and vibrates with the vertical axis or stem *e*, which is held by and plays freely in a socket in the standard *f*. The thread-carrier is grooved in its periphery and contains the usual eye in the groove and through the end, the course of the thread from the spool being shown by the line *x x*. The thread-carrier is moved by a crooked arm, *g*, shaped as shown in the drawings, and notched at the end next to the thread-carrier, so as to receive and take on a pin, *h*,

projecting from the axis of the thread-carrier. The other end of the arm is fast to a vertical axis or rock-shaft, *i*, which rocks on center bearings on the ends of the screws *j j*, receiving its motion in one direction from the feed-cam *k* by means of the arm *l*, attached to the rock-shaft by a set-screw, so as to be adjustable, and is moved in the opposite direction by the action of the spring *m* upon the arm *g*. The second pad *n* is secured to the frame *a* by the spring *o*. The spool of under thread is supported by a spool-bearer, *p*, which is hinged to the frame *a* at *q*, so as to be readily set in different position. An annular weight, *s*, slipped on the spool-wire over the spool, or any suitable means of tension on the under thread, may be used. An adjusting-screw, *r*, determines the extent of motion of the lever that moves the thread-carrier.

I have shown the device that communicates motion from the cam that advances the cloth to the thread-carrier composed of several pieces; but the same may be readily made in one piece, if desired. By thus taking the motion for the thread-carrier from the cam employed to advance the cloth, and by so constructing and organizing the thread-carrier and other separately-organized mechanism that it can be at once brought into co-operative action with the operative parts of the Wheeler & Wilson machine, without other change than to lay aside for the time the bobbin and ring-slide, I have succeeded in producing a valuable result, because many can not afford two separate machines, and have generally to choose which stitch they can best afford to dispense with, which sometimes is not easy to determine, as both the lock-stitch and the double-loop stitch are of nearly equal value in different departments of family sewing.

I claim—

1. The combination of the under-thread carrier with the needle and rotating hook and operative parts of a Wheeler & Wilson sewing-machine, (except the bobbin and ring-slide,) substantially as and for the purposes described.

2. The separate organization of the under-thread carrier, with its lever, in an independent frame in such manner that it may be at once attached to the Wheeler & Wilson sewing-machine in the place of the ring-slide, so as to bring the thread-carrier and its actuating-lever in co-operative relation with the hook and needle and the cam that advances the cloth, substantially as described.

J. J. SIBLEY.
